UNITED STATES PATENT OFFICE.

CHARLES B. FRANKLIN, OF TUCSON, ARIZONA.

MITER BOX.

Application filed July 30, 1925. Serial No. 47,112.

This invention relates not only to the general construction of miter boxes, but deals also with unique saw-guiding means.

One object of the invention is to provide 5 an unusually simple and inexpensive, yet an efficient and very desirable miter box which may readily be adjusted for cutting stock at any desired angle.

Another aim is to provide a construction 10 which may be readily disassembled and carried in a tool box.

A still further aim is to provide a miter 15 box of a type having guiding rollers for an ordinary saw, and equipped with novel means whereby said rollers may be relatively adjusted.

With the foregoing in view, the invention resides in the novel subject matter herein-after described and claimed, the description 20 being supplemented by the accompanying drawings.

Figure 1 is a top plan view partly broken away and in horizontal section.

Figure 2 is a side elevation.

25 Figures 3 and 4 are vertical sectional views as indicated by lines 3-3 and 4-4 of Fig. 1.

Figure 5 is a horizontal sectional view 30 partly in plan, as indicated by line 5-5 of Fig. 4.

Figure 6 is an elevation showing primarily the extension saw-guiding means.

Figure 7 is a top plan view of the base 35 plate of the device.

Figure 8 is an edge view of the plate shown in Fig. 7.

In the drawings above briefly described, 40 the numeral 1 designates a bottom board which may be of any desired proportion. Secured by screws or the like 2, to the lower side of this board 1, is a base plate 3 of circular outline, said plate having a continuous groove 4 in its edge, forming a guide track. The plate 3 is provided with 45 a downwardly projecting stepped stud 5 which is concentric with the edge of said plate, the lower end of the stud being normally spaced above the work-bench or the like upon which the miter box is used, by 50 appropriate legs 6 which are suitably secured to the bottom board 1, as shown for instance in Fig. 2.

Two horizontally elongated members 7 55 are provided with depressed central portions 8 which cross each other and extend under the base plate 3, said members 7 hav-

ing openings 9 through which the stud 5 passes, a nut 10 being threaded on the lower end of this stud. Preferably, a washer 11 is interposed between the two members 7 60 and another washer is positioned between the lowermost of the members and the nut 10. When this nut is tightened, it cannot lock the members 7 against pivotal movement about the stud 5, due to the shouldered 65 formation of the latter. Hence, the members 7 may be swung to different angular positions with respect to the bottom board 1. For locking these members in any desired adjusted position, they are provided 70 with spring-pressed detents 13 engageable with a toothed segment 14 which is secured to the bottom of the board 1, said detents preferably having releasing triggers 15 at 75 the lower sides of the members 7. The ends of the members 7 carry saw-guiding means, and to effectively stabilize said members and hold them against chattering when the saw is being operated, said members are provided with projecting lugs 16 received slidably in the groove 4. Opposed portions of the plate 3 at the lower side of this groove, may well be cut away as indicated at 17, to allow the lugs 16 to be engaged with the groove when assembling the device, or disengaged from said groove when disassembling. If desired, however, other provision 80 could be made to permit this assembly and disassembly.

The ends of the members 7 project laterally beyond the board 1 and are provided with upstanding bosses 18 to which upstanding rigid posts 19 are secured by screws or the like 20, two of these posts being provided at each end of each member 95 7. These posts are of such form as to provide their inner sides with longitudinal channels 21, and said posts are provided with upper end walls 22 at the upper ends 100 of said channels, said walls being preferably formed separately from the body portions of the posts and secured in place by screws 23 as shown in Fig. 5. The end walls 22 are formed with slots 24 in which flat side 105 bearings 25 are slidably mounted, said bearings having lateral flanges 26 adjacent the lower sides of the walls 22 and being provided with upstanding studs 27 which rise to points above said walls. Washers 28 and nuts 29 are provided on the studs 27 and when the nuts are tightened, the bearings 25 are held in adjusted positions with re-

gard to the end walls 22 and slots 24 thereof.

The portions of the bosses 18, immediately below the end walls 22, are formed with slots 30 which receive studs 31 projecting downwardly from bearings 32 which rest on said bosses, said studs being provided with nuts 33, which when tightened, lock the bearings 32 in adjusted position.

10 The bearings 25 and 32 are engaged by trunnions 34 and 35 which project from upper and lower metal plugs 35 and 36, said plugs being disposed in sockets 37 in the ends of rollers 38, these rollers being preferably formed of wood. Metal rods 39 extend through axial bores 40 formed in the rollers 38 and serve to tightly connect the plugs 35 and 36. Preferably, the rods 39 are integral with the lower plugs 36 and 20 are threaded into the upper plugs 35 as shown.

By the construction and arrangement shown and described, the closely spaced, parallel, saw-guiding rollers at opposite ends 25 of the members 7, are rotatably mounted and mounted for any necessary adjustments, in a very rigid, efficient and desirable manner.

If desired, saw-guiding extensions may be 30 employed, as shown in Fig. 6. In this view, vertically alined bearings 41 are shown carried by the posts 19 at opposite sides of the saw path. In these bearings, vertical rods 42 are slidably received, said rods being of a length to project upwardly beyond the posts and having their upper ends bent downwardly as at 43 into parallel relation, forming auxiliary saw guiding means.

At suitable intervals, one edge of the bottom board 1 is provided with upstanding stock-guiding posts 44 which are suitably secured to metal plates 45, the latter being in turn secured to the board 1 by screws or the like 46, as shown most clearly in Fig.

45 3. Two of these posts are preferably so located, as to indicate the proper positions for the members 7, when they are set for cutting either right or left hand miters of 45°. Thus, if anyone has changed the adjustment of the box after it has once been set, and someone wishes to cut a 45° miter, he can tell at a glance before the cut has been made, that the adjustment of the box has been changed. He can then readily re-adjust the device to the proper extent and make the cut. Thus, there is no danger of wasting any material by making the wrong cut thereon accidentally.

To indicate when either of the members 60 7 is set for a cut at right angles to the length of the stock, a pair of auxiliary posts 47 are preferably provided, suitably mount-

ed at one edge of the board 1, said posts being adapted to receive between them, the saw.

At 48, I have shown saw guiding means which consists of posts and rollers such as those above described, said means being located at one end of the board 1, in position to guide the saw for cutting at right angles 70 to the length of the stock, if it is not desired to change the adjustment of the other saw-guiding means.

It will be seen from the foregoing that my invention is rather simple and inexpensive, yet that it will be highly efficient. Particular attention is directed to the fact that the device may be quickly and easily disassembled and compactly positioned for carrying in small space. For instance, all 80 of the metal parts and the wooden rollers may readily be carried in an ordinary tool box and when their use is necessary, they may be quickly and easily attached to an ordinary two by six or two by eight, so as to 85 retain them in operative relation and produce an effective miter box.

As excellent results are obtainable from the details disclosed, they are preferably followed. However, within the scope of the 90 invention as claimed, numerous modifications may be made.

I claim:—

1. A miter box comprising a bottom member, a base plate secured to the lower side 95 thereof and having horizontal trackage curved about a central point, a pair of crossed horizontally elongated members under the bottom member and base plate and pivoted to the latter at said central point, 100 said crossed members each having a portion slidably engaged with said trackage, saw guides rising from the ends of said crossed members, and means for holding said members in angularly adjusted positions. 105

2. A miter box comprising a bottom member, a base plate of circular outline secured to the lower side of said bottom member, said base plate having a groove in its edge and a downwardly projecting bearing stud 110 at its center, a pair of crossed centrally depressed horizontally elongated members under said bottom member and base plate and each provided with a portion slidably received in said groove, said crossed 115 members having openings through which said bearing stud passes, saw guides rising from the ends of said crossed members, and means for holding these members in angularly adjusted positions. 120

In testimony whereof I have hereunto affixed my signature.

CHARLES B. FRANKLIN.
